UNITED STATES PATENT OFFICE

JAMES C. LAMB, OF WARSAW, VIRGINIA

RADIATOR TRUCK

Application filed August 10, 1931. Serial No. 556,218.

This invention relates to trucks or portable devices especially adaptable for transporting radiators from one place to another and has for the primary object, the provision 5 of a device of the above stated character which may be easily and quickly placed under a radiator and positioned to support the radiator clear of the floor or ground, so that the radiator may be conveyed to a desired place 10 with the least expenditure of manual labor.

Another object of this invention is the provision of a pair of portable devices adapted to be placed into engagement with the ends 15 of a radiator and having handles which when swung vertically and secured to the radiator, position said radiator in an elevated position ready to be pushed to a desired place.

A further object of this invention is the provision of securing means on the handles 20 which may be easily and quickly brought into engagement with certain coils or sections of the radiator for locking the portable devices in position to support the radiator clear of the ground or floor and which may be easily 25 detached from the radiator when desiring to lower the latter and remove the portable devices therefrom.

A further object of this invention is the provision of adjustable hand grips on the 30 handles to permit persons to readily lift and carry the device with the radiator thereon.

With these and other objects in view, this invention consists in certain novel features 35 of construction, combination and arrangement of parts to be hereinafter more fully described and claimed.

For a complete understanding of my invention, reference is to be had to the following 40 description and accompanying drawings, in which

Figure 1 is a side elevation illustrating a radiator supported by my invention.

Figure 2 is a side elevation partly in section illustrating one of the trucks or portable 45 devices.

Figure 3 is a sectional view taken on the line 3-3 of Figure 2.

Figure 4 is a sectional view, taken on the 50 line 4-4 of Figure 2.

Figure 5 is a side elevation illustrating a clamp.

Figure 6 is an end elevation illustrating the clamp.

Figure 7 is an end elevation illustrating 55 one of the devices occupying its initial position to the end of the radiator.

Figure 8 is a detail sectional view illustrating 60 the clamp securing the truck or portable device to the legs of the radiator.

Referring in detail to the drawings, the numeral 1 indicates a radiator adapted to be supported by trucks or portable devices as shown in Figure 1 and each of the trucks or 65 portable devices is identical in construction with the other so reference to one specifically is thought sufficient for both.

A base or frame 2 includes an elongated member 3 which has formed thereon adjacent its ends angularly disposed plates 4 to which are swivelled casters 5 of a conventional type which are capable of turning about a vertical axis so that during the use of the device 70 the steering thereof will be made comparatively easy.

A substantially U-shaped handle 6 has its ends secured to the plates 4 and includes side members 7 connected at their upper ends by an end member 8 adapted to extend transversely of a radiator and in a plane above the same when the device is applied to the radiator.

The side members 7 are disposed directly above the casters 5 while the member 3 is positioned laterally thereof and has formed intermediate its ends a projection 9 adapted to fit or engage under the end section or coil of a radiator between the legs thereof as shown in Figures 1 and 7 with the casters and 85 handle located a short distance inwardly of the respective end of the radiator when the device is in an operative position as shown in Figure 1. The portable device is first positioned against a radiator as shown in Figure 90 7 with the handle disposed at an inclination and by swinging said handle into a vertical position as shown in Figure 1 the end of the radiator will be elevated. To retain the handle in a vertical position, a locking device 10

is slidably mounted on the handle and is 95 100

adapted to be brought into engagement with the radiator between a pair of the sections thereof preventing the handle from again tilting to an inclined position as shown in Figure 7. The locking device 10 comprises a bar 11 having sleeves 12 at the ends thereof of which are slidably mounted on the side members 7 of the handle. Spaced wedge-like lugs 13 are carried by the bar 11 and are adapt'd to fit tightly between a pair of sections or coils of the radiator and at opposite sides of the connecting portion between said coils or sections, thus holding the handle vertically as well as retaining the radiator in a vertical position without the possibility of the radiator rattling.

A substantially T-shaped bracket 14 has the head portion 15 thereof positioned under the radiator and in engagement with the legs thereof and the stem portion 16 thereof extended between the legs of the radiator. An adjusting bolt or screw 17 is carried by the stem 16 of the bracket and is adapted to be turned into a recess of a lug 18 formed on the member 3 and disposed opposite to the lug 9, thus the clamp 14 firmly attaching the radiator to the truck or portable device against accidental displacement.

When moving a radiator from one place to another, a portable device or truck is placed at each end of the radiator and when the handles thereof are swung vertically and secured to the radiator in the stated position, the radiator will be firmly supported in an elevated position ready to be transported to any place desired.

The handle 6 has secured to the side members 7 thereof adjustable hand grips 19 each including a tubular portion 20 having formed integral with one end a sleeve 21 slidably receiving one of the members 7 of the handle, and the opposite end of the tubular member 20 is screw-threaded to receive an adjusting cap 22. A rod 23 is slidably mounted in the tubular member 20 and one end extends through an aperture in the sleeve 21 for engagement with the handle while the opposite end engages the cap 22 and by adjusting the cap 22 on the tubular member, the rod 23 will be forced into tight engagement with the handle consequently firmly securing the hand grip to the handle and providing a construction which will permit the hand grip to be adjusted vertically and laterally relative to the handle 6 when desired.

The hand grips properly adjusted permit the radiator to be carried by two or four men with a minimum expenditure of manual effort without the hands of the men coming in contact with the radiator, thereby reducing to a minimum any form of contact with the radiator, thereby assuring protection to the finish thereof.

With the radiator supported in the foregoing manner it is possible to move the lat-

ter from one place to another over a comparatively smooth surface by a single person or where it is necessary, the radiator may be lifted and carried by two or four men.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A truck for radiators comprising a frame to engage under an end of a radiator, ground engaging elements for the frame and arranged at opposite sides of the radiator and between the ends of the latter and providing a fulcrum on which the frame may swing, means on the frame to swing the latter on its ground engaging elements to elevate the radiator, and means detachably securing said first means to the radiator.

2. A truck for radiators comprising a substantially U-shaped frame arranged transversely of one end of a radiator, means on the frame to engage under said end of the radiator, ground engaging elements carried by the ends of the frame and arranged at opposite sides of the radiator and between the ends of the latter and providing a fulcrum for the frame, a handle connected to the frame and adapted to be moved into a vertical position for elevating the radiator, and means detachably connecting the handle to the radiator.

3. A truck for radiators comprising a substantially U-shaped frame arranged transversely of one end of a radiator, means on said frame to engage under said end of the radiator, rollers carried by the ends of the frame and disposed at opposite sides of the radiator and between the ends of the latter, a U-shaped handle secured to the ends of the frame and adapted to be swung vertically for elevating the radiator, and means carried by the handle to engage the radiator for securing the latter to the handle.

4. A truck for radiators comprising a substantially U-shaped frame arranged transversely of one end of a radiator, means on said frame to engage under said end of the radiator, rollers carried by the ends of the frame and disposed at opposite sides of the radiator and between the ends of the latter, a U-shaped handle secured to the ends of the frame and adapted to be swung vertically for elevating the radiator, a bar slidably on said handle, and means carried by said bar to engage between the coils of the radiator.

5. A truck for radiators comprising a substantially U-shaped frame arranged transversely of one end of a radiator, means on said frame to engage under said end of the radiator, rollers carried by the ends of the

frame and disposed at opposite sides of the radiator and between the ends of the latter, a U-shaped handle secured to the ends of the frame and adapted to be swung vertically for elevating the radiator, a bar slideable on said handle, and spaced elements carried by said bar to fit between coils of the radiator.

6. A radiator comprising a substantially U-shaped frame arranged transversely of one end of a radiator with the ends thereof disposed at opposite sides of the radiator and between the ends of the latter, rollers carried by the ends of the frame, a lug carried by the frame and adapted to fit under the radiator, means cooperating with the lug and frame for detachably securing the radiator to the frame, a handle connected to the ends of the frame and adapted to be swung vertically for elevating the radiator, and means detachably connecting the handle to the radiator.

7. A radiator comprising a substantially U-shaped frame arranged transversely of one end of a radiator with the ends thereof disposed at opposite sides of the radiator and between the ends of the latter, rollers carried by the ends of the frame, a lug carried by the frame and adapted to fit under the radiator, means cooperating with the lug and frame for detachably securing the radiator to the frame, a handle connected to the ends of the frame and adapted to be swung vertically for elevating the radiator, means detachably connecting the handle to the radiator, and adjustable hand grips on the handle and arranged at opposite sides of the radiator.

8. A truck for radiators comprising a frame, rollers for said frame, a lug on said frame and adapted to fit under one end of a radiator when the frame is arranged transversely of the radiator, a clamp engaging the lug and the radiator for securing the latter to the frame, a handle for the frame for tilting the latter on the rollers to elevate the radiator, and means detachably connecting the handle to the radiator.

In testimony whereof I affix my signature.
JAMES C. LAMB.
